(57) **CLAIM**

The ornamental design for a vaporizer for tobacco, medications, and the like, as shown and described.

DESCRIPTION

FIG. 1 is a left side elevational view of a vaporizer for tobacco, medications, and the like showing my new design;
FIG. 2 is a right side elevational view thereof;
FIG. 3 is a top plan view thereof;

FIG. 4 is a bottom plan view thereof;

FIG. 5 is a rear elevational view thereof; and,

FIG. 6 is a front elevational view thereof.

Any portion of any figure shown in broken lines are for environmental purposes only and form no part of the claimed design.
